CLAIM

The ornamental design for an snap together orchard bin, as shown and described.

DESCRIPTION

FIG. 1 is a top plan perspective view of the present design, a snap together orchard bin.

FIG. 2 is a front side elevational view of the present design, shown in FIG. 1; and,

FIG. 3 is a left side elevational view of the present design, shown in FIG. 1.

Front and rear sides are identical, as are the left and right sides.
